DRY SHAVER

Emmett Wilson, Los Angeles, Calif.

Application April 5, 1937, Serial No. 135,115

4 Claims. (Cl. 30—43)

My invention relates to a dry shaver to be used for shaving hair from the face or other parts of the body, and the objects of my invention are:

First, to provide a new and novel dry shaver 5 head for dry shavers;

Second, to provide a dry shaver in which the blade is double edged and may be reversed so that both edges may be used;

Third, to provide a dry shaver head in which 10 the blade is positioned at an obtuse angle from the axis of the handle end;

Fourth, to provide a dry shaver of this class with novel means for reciprocating the blade;

Fifth, to provide a dry shaver of this class with 15 novel adjusting means;

Sixth, to provide a dry shaver with a reciprocating blade in the head and arranged to be reciprocated by means of a rotatable stem passing through the handle of the shaver, a portion of 20 which is cut away to expose the shaft or stem so that it may be engaged by a suitable device for imparting rotary movement thereto;

Seventh, to provide a dry shaver of this class in which the number of parts employed in 25 constructing the shaver is reduced to a minimum, there being required only a handle, a blade, guard, and a shaft in the production of my shaver;

Eighth, to provide a dry shaver of this class in 30 which the blade is vibrated or reciprocated by means set in motion manually, which means is accessible at all times and which does not interfere with the normal use of the dry shaver;

Ninth, to provide a dry shaver of this class 35 whereby extremely high rate of vibration or reciprocation may be obtained; and

Tenth, to provide a dry shaver of this class which is very simple and economical of construction, durable, efficient and which will not readily 40 deteriorate or get out of order and which is very economical to use.

With these and other objects in view as will appear hereinafter, my invention consists of certain novel features of construction, combination 45 and arrangement of parts and portions as will be hereinafter described in detail and particularly set forth in the appended claims, reference being had to the accompanying drawing and to the characters of reference thereon which form 50 a part of this application in which:

Figure 1 is a side elevational view of my shaver complete shown ready for use; Fig. 2 is a longitudinal sectional view taken at right angles to that of Fig. 1 from the line 2—2 of Fig. 1 and 55 showing some of the parts and portions in elevation to facilitate the illustration; Fig. 3 is an enlarged sectional view of a fragmentary portion as shown in Fig. 2 of the dry shaver head and its connecting parts, and Fig. 4 is an enlarged sectional view from the line 4—4 of Fig. 2 showing 60

some of the parts and portions broken away to facilitate the illustration.

Similar characters of reference refer to similar parts and portions throughout the several views of the drawing.

The handle casing 1, handle casing end 2, shaver head 3, blade 4, cap 5, shaft 6, shaft adjusting screw 7, fly wheel 8 and shaft bearings 9, 10, and 11 constitute the principal parts and portions of my dry shaver.

The handle casing 1 is provided with a handle portion 1a of a diameter adapted to be easily grasped by the fingers and thumb for holding the shaver in position for shaving and is hollow to make it light. It is provided on its extended end 15 with an enlarged cylindrical portion 1b which is also hollow and adapted to receive and enclose the fly wheel 8 shown best in Fig. 2 of the drawing. This fly wheel 8 provides the motive power for reciprocating the blade of the shaver. 20 Mounted in the extended end of the enlarged cylindrical portion 1b is the handle casing end 2 which is screw threaded therein by means of screw threads 2a, and mounted centrally in an annular cage 2b in the end member 2 is a bearing 9 which is adapted to receive the reduced extended end 6a of the shaft 6 and the fly wheel 8 is secured on the shaft immediately above this reduced portion 6a. The handle member 1 is cut away at one side at 1c, to provide ready access to 30 a knurled surface 6b on the shaft 6. This knurled surface 6b is for engagement with a round leather belt, cord, or other device which may be stretched, and by engaging this knurled surface 6b with said stretched device, the fly wheel 8 may be 35 made to revolve at a rapid speed by moving the handle member along said belt or other device. The shaft is provided with a bearing 11 secured in the handle portion adjacent the knurled portion 6b. It will be here noted that the construction so far described is substantially the same as the razor blade operating means described and disclosed in the patent issued to me by the United States Patent Office November 19, 1935, Patent No. 2,021,344.

The shaft 6 near its extended end is provided with a reduced portion 6c which is mounted in a bearing in the forwardly extending end 10 of the handle casing 1, this reduced portion 6c being concentric with the shaft 6. Extending from 50 this portion 6c is another reduced end portion 6d which is mounted eccentric with the shaft 6 shown best in Fig. 3 of the drawing, and this eccentric portion 6d is provided with an offset point 6e at its extremity, which point is concentric and 55 positioned directly in line with the axis of the shaft 6 so that when the point 6e is engaged by the shaft adjusting screw 7, the point 6e is pivoted centrally with the shaft adjusting screw 7 so that when the shaft revolves, the eccentric 60

portion **6d** operates eccentrically while the point **6e** being concentric with the shaft **6** remains in constant central position with the shaft adjusting screw **7**. The front extended end **1d** of the handle casing member **1** is reduced in diameter and adapted to receive an annular hollow cylindrical portion **3a** of the shaver head **3** which fits snugly on the portion **1d** and forms a tight fit therewith.

10 The shaver head **3** is provided with a slotted portion **3b** which is positioned on an angle with the cylindrical portion **3a** as shown best in Figs. 2 and 3 of the drawing, the side **3c** being open and over which is mounted the cap **5**. This cap **5** is 15 provided with fine slots **5a** in its front face and is U-shaped in cross section and is supported on the portion **3b** by means of screws **5b** which extend into the member **3b** on opposite sides for holding the cap member rigidly in position on the head 20 portion **3b**. The slot in the head portion **3b** is adapted to receive the blade **4** which is adapted to reciprocate therein. This blade is provided with a plurality of narrow slots **4a** which conform with the slots **5a** in the cap **5** when they 25 are in certain relative position and forms shearing portions between the slotted portions of the blade and cap with the reciprocation of the blade, thus clipping the hair which extends inwardly through the slots **5a** and are sheared by the ridge 30 portions **4b** of the blade between the slots **4a**.

This blade **4** is provided with slots **4a** and ridges **4b** on opposite sides so that it may be reversed and both edges used and it is supported in its relation relative to the cap **5** by means of screws 35 **3d** at the opposite ends of the head member as shown best in Fig. 4 of the drawing. This blade **4** is also provided with a slot **4c** through which the eccentric portion **6d** of the shaft **6** extends so that when the shaft revolves, this eccentric 40 portion causes the reciprocation of the blade **4**, the head being provided with an orifice **3e** large enough to permit the eccentric movement of the portion **6d**. It will be here noted that any wear in the shaft as far as end thrust is concerned 45 may be taken up gradually by means of the shaft's adjusting screw **7**.

The operation of my dry shaver is as follows: When it is desired to shave, the dry shaver is taken by the handle **1** at the portion **1a** and the 50 knurled portion **6d** pressed against a strap or other long object and moved rigidly in one direction which causes the fly wheel to revolve rapidly. Then the front face portion of the cap **5a** is positioned to engage the face, and the shaver 55 moved along. The revolution of the fly wheel **8** causes the reciprocation of the blade **4** and the hair is clipped close to the skin. It has been found that the fly wheel when properly started will revolve for several minutes under dry shaving 60 operation.

Though I have shown and described a particular construction, combination, and arrangement of parts and portions, I do not wish to be limited to this particular construction, combination, and arrangement but desire to include in the scope of my invention the construction, combination, and arrangement substantially as set forth in the appended claims.

Having thus described my invention, what I 70 claim as new and desire to secure by Letters Patent is:

1. In a dry shaver, the combination with a handle, of a head positioned at an obtuse angle to said handle, a blade reciprocably mounted in 75 said head, said blade provided with alternate

grooves and ridges in its edge, a cap member provided with alternate grooves and ridges in engagement with the edge of said blade and secured to said head, said blade having grooves and ridges in its opposite edges whereby it is reversible, said blade having a slot extending transversely therein, an eccentric shaft in engagement with the walls of said slot for reciprocating said blade, said shaft provided with a point concentric with the shaft on the extended end of the eccentric portion thereof, an adjustable bearing in connection therewith, and fly wheel means in connection with said shaft for revolving the same.

2. In a dry shaver, the combination with a handle, of a head positioned at an obtuse angle to said handle, a blade reciprocably mounted in said head, said blade provided with alternate grooves and ridges in its edge, a cap member provided with alternate grooves and ridges in engagement with the edge of said blade and secured to said head, said blade having grooves and ridges in its opposite edges whereby it is reversible, said blade having a slot extending transversely therein, an eccentric shaft in engagement with the walls of said slot for reciprocating said blade, said shaft provided with a point concentric with the shaft on the extended end of the eccentric portion thereof, an adjustable bearing in connection therewith, fly wheel means in connection with said shaft for revolving the same, a recess in the handle of said shaver and extending partially around said shaft, and said shaft provided with a knurled portion for engagement by friction device to apply rotary motion to said shaft.

3. In a dry shaver, the combination with a handle, of a head fixedly positioned at an angle other than a right angle to said handle, a blade reciprocably mounted in said head, said blade provided with alternate grooves and ridges in its edge, a cap member provided with alternate grooves and ridges in engagement with the edge of said blade at a right angle to the plane of the blade and secured to said head, said blade also having a slot extending transversely therein, an eccentric shaft in engagement with the walls of said slot for reciprocating said blade, said shaft provided with a point concentric with the shaft on the extended end of said eccentric portion thereof, and an adjustable bearing in connection therewith.

4. In a dry shaver, the combination with a handle, of a head fixedly positioned at an angle other than a right angle to said handle and provided with a blade supporting slot extending in opposite directions to the longitudinal axis of said handle, a relatively wide thin flat blade reciprocably mounted in said slot and extending outwardly of said slot at one side, said blade provided with alternate grooves and ridges in its edge, a cap member provided with alternate grooves and ridges extending straight across its edge face in engagement with the edge face only of said blade at a right angle to the plane of the blade and secured to said head on opposite sides 65 of said blade, said blade having grooves and ridges in its opposite edges whereby it is reversible for use, said blade having a slot extending transversely therein, an eccentric shaft in engagement with the walls of said slot for reciprocating said blade, said shaft provided with a point concentric with the shaft on the extended end of the eccentric portion thereof and an adjustable bearing in connection therewith.

EMMETT WILSON. 75
